UNITED STATES PATENT OFFICE.

WILLIAM A. HOLT, OF MEBANE, NORTH CAROLINA, ASSIGNOR TO THE MEBANE BEDDING COMPANY, INC., OF MEBANE, NORTH CAROLINA.

WIRE MATTRESS FABRIC.

1,129,392.

Specification of Letters Patent. Patented Feb. 23, 1915.

Application filed April 26, 1913. Serial No. 763,866.

To all whom it may concern:

Be it known that I, WILLIAM A. HOLT, citizen of the United States, residing at MEBANE, in the county of Alamance and State 5 of North Carolina, have invented certain new and useful Improvements in Wire Mattress Fabrics, of which the following is a specification.

My invention relates to bed-bottom fabrics and more particularly relates to that 10 class of fabrics which are made of interconnected bent wire units.

The primary object of my invention is to provide a fabric of this class so constructed 15 that while it will yield readily to the weight of a body, yet a heavy person lying on one side of the mattress will not affect the other side to depress it and thus the lighter person will not be in an uncomfortable position and 20 under a constant tendency to roll toward the heavier person.

A further object of the invention is to provide an improved bed bottom fabric wherein diagonal strains are obviated, these 25 diagonal strains being objectionable for the reason that they act to draw in the longitudinal edges of the fabric and therefore require the longitudinal edges to be positively connected to a side rail.

30 A further object of the invention is the provision of very simple units which may be readily linked up with each other so as to form a fabric of the character described.

Still another object is to so construct the 35 units from which the fabric is composed that the members which would be likely to carry or transmit the diagonal strain before referred to, are spaced from each other and not connected so that the diagonal strain is 40 interrupted across the entire fabric, this being secured by so forming the units and so arranging them with relation to each other that the members diagonally extending in one direction alternate with members diagonally extending in another direction.

45 Other objects will appear in the course of the following description.

My invention is illustrated in the accompanying drawings wherein:

50 Figure 1 is a top plan view of a mattress constructed in accordance with my invention. Fig. 2 is a section on the line 2—2 of Fig. 1. Fig. 3 is a perspective view of one

of the N-shaped links. Fig. 4 is a perspective view of one of the single straight links 55 used in connecting the N-shaped links.

Corresponding and like parts are referred to in the following description and indicated in all the views of the accompanying drawings by the same reference characters. 60

Referring to the drawings, 2 designates a side rail and 3 the opposed end rails of a spring mattress frame, said rails being of any suitable construction but are preferably in the form of angle bars rigidly united at 65 the corners by bolts and nuts. I wish it understood that I do not wish to be limited to any particular construction for this frame as it forms no part of my invention.

My improved mattress fabric is composed 70 mainly of N-shaped unit links 4, each comprising a leg 5, a diagonally extending leg 6 and a leg 7. At the intersection of the leg 6 with the legs 5 and 7, loops 8 are formed whereby the links may be engaged 75 with each other, and at the ends of the legs 5 and 7 vertically disposed hooks or loops 9 are formed for the same purpose. I also use straight links 10 illustrated in Fig. 4. It will be seen from Fig. 1 that I arrange these 80

85 N-shaped links 4 in transversely extending rows or series and that the links of each row are reversely disposed to the links of the next adjacent rows. It is, of course, necessary that the eyes or loops 8 of one 85 row shall come opposite to and join with the hooks or loops 9 of the links of the next adjacent rows and therefore it is necessary to dispose the N-shaped links of one row or series in staggered relation to the N- 90 shaped links of the other row or series. Thus in row A, only N-shaped links are used and these links are spaced from each other. In row B, however, the N-shaped links are 95 reversed relative to the row A and are also placed in staggered relation so that the leg of the first N-shaped link of the row B will engage with the eye or loop 8 of the first N-shaped link of row A. It is necessary, therefore, to use intermediate links to connect the first N-shaped link of row A with the first N-shaped link of row C. This is done by using the intermediate link 10 and also connecting the loop of the first N- 100 shaped link of row C with the loop of the first N-shaped link of row A by means of the

105

diagonally disposed link 10^a. It is also necessary to use the straight links 10^a at intervals to connect the loop 8 of one N-shaped link with the loop 8 of another N-shaped link in the row or series next to the row or series adjacent to the first-named link, as illustrated in the series B at 10^a.

While I have shown five transversely disposed series of linked units, and three longitudinal series, it will of course be understood that I may use any desired number depending upon the size of the mattress. The transverse series of links at each end of the mattress are connected to the frame by means 15 of coil springs 11 which engage with the loops 8 and hooks 9 of the N-shaped links.

It is to be particularly pointed out that the diagonally disposed members 6 break joints with each other as it were, that is, 20 there is no line of diagonal members extending continuously across the mattress fabric, but that the alternate diagonal members, whether these are the diagonally arranged bars 6 or the diagonally arranged 25 links 10^a, extend practically at right angles to each other. By this arrangement I provide a mattress fabric including a plurality of diagonally disposed linking members arranged in a plurality of transverse series, 30 these linking members being either the links 10^a or the members 6 of the N-shaped links, the diagonal linking members of one series being disposed at an angle to the diagonal linking members of the next adjacent series.

35 It is by this construction that I avoid the diagonal strains before referred to which tend to cause the contraction of the middle portion of the mattress fabric when weight is disposed upon the mattress.

40 A mattress fabric constructed in accordance with my invention has ample resiliency, but it permits a portion of the mattress to yield without more than slightly affecting the remainder of the mattress, and it is possible for one-half of the fabric to be very 45 greatly depressed as by the weight of a heavy person while the remainder of the fabric remains practically normal or is depressed slightly by the weight of a light 50 person. There is no tendency therefore for the mattress to be inclined from one edge downward to the lowest point of the mattress fabric as is usual in wire mattresses, and therefore there is no tendency for the 55 lighter person to roll toward the heavier person.

The fabric as above described is very simple, the links are easy to make and easy to assemble, and the mattress is strong and 60 durable.

What I claim is:

1. A mattress fabric including N-shaped units having two parallel legs and a diagonal leg joining the parallel legs, the units 65 being arranged in a plurality of series, the

diagonal legs of one series of units being disposed at an angle to the diagonal legs of the next adjacent series of units.

2. A mattress fabric including a plurality of series of N-shaped units, the units of 70 one series being reversely arranged to the units of the next adjacent series.

3. A mattress fabric including a plurality of series of N-shaped units extending transversely across the mattress, the units of one 75 series being reversely arranged to the units of the next adjacent series.

4. A mattress fabric including a plurality of series of units, each unit comprising parallel legs and a diagonal leg, these units being formed with eyes at the intersection of the diagonal leg with the parallel legs, the ends of the parallel legs being formed with vertically disposed hooks, the units of one series being reversely arranged to the units 85 of the next adjacent series and having staggered relation thereto and being interconnected through the said eyes, and straight connecting members having hooked ends and operatively engaging certain of the 90 units of one series with certain of the units of the alternate series.

5. A mattress fabric including at both ends of the mattress a transversely extending series of N-shaped units, the units of one 95 series being spaced from each other, and a plurality of intermediate series of N-shaped links connected to each other and to the two first-named series, and the units of each of the intermediate series being connected to 100 each other by diagonal members across the entire extent of the mattress.

6. A metal fabric for bed-springs, comprising a multiplicity of wire units arranged in rows, each unit consisting of an 105 integral N-shaped link.

7. A metal fabric for bed-springs, comprising a multiplicity of wire units arranged in rows, each unit consisting of a pair of parallel straight portions integrally 110 connected by an inclined portion.

8. A metal fabric for bed-springs, comprising a multiplicity of wire units arranged in rows, each unit consisting of an integral N-shaped link, and each free end 115 thereof terminating in a hook or loop.

9. A metal fabric for bed-springs, comprising a multiplicity of wire units arranged in rows, each unit consisting of a pair of parallel straight portions connected 120 by an inclined portion extending from a point adjacent to one end of one straight portion to a point adjacent to the opposite end of the other straight portion, each of said straight portions terminating at its end 125 in a loop or hook.

10. A metal fabric for bed-springs, comprising a multiplicity of wire units arranged in rows, each unit consisting of a pair of parallel straight portions connected 130

5 by an inclined portion extending from a point adjacent to one end of one straight portion to a point adjacent to the opposite end of the other straight portion, and having intermediate the juncture points of such inclined part and the ends of such straight portions laterally deflected bulged portions.

11. A metal fabric for bed-springs, comprising a multiplicity of wire units arranged in rows, each unit consisting of a pair of parallel straight portions connected by an inclined portion extending from a point adjacent to one end of one straight portion to a point adjacent to the opposite end of the other straight portion, each of said straight portions terminating at its end in a loop or hook and at its opposite end in a bulged formed portion.

12. A metal fabric for bed-springs, comprising a multiplicity of wire units arranged in rows, each unit consisting of a pair of parallel straight portions connected by an inclined portion extending from a point adjacent to one end of one straight portion to a point adjacent to the opposite end of the other straight portion, each of

said straight portions terminating at one end in a loop or hook and intermediate said end and its point of connection with the inclined portion in a projecting portion. 30

13. A link for a metal fabric comprising an N-shaped member, consisting of a pair of parallel members connected by an inclined member, each of said parallel members terminating in a loop or hook, said 35 loops or hooks being at opposite ends of the link.

14. A link for a metal fabric comprising an N-shaped member, consisting of a pair of parallel straight portions connected by 40 an inclined portion, each of said straight portions terminating at one end in a loop or hook and having intermediate said end and its point of connection with the inclined portion a projecting portion. 45

In testimony whereof I affix my signature in presence of two witnesses.
